GEORGE D. SCHERMERHORN, OF READING, MICHIGAN

FOLDING CHAIR

Application filed April 9, 1928. Serial No. 268,397.

My invention relates to an improved folding chair.

An object is to provide a folding chair of a sturdy and rigid construction adapted for use in assembly halls and the like and which may be folded flat for storage, which chair is so constructed that the back, seat and legs fold within the uprights into alignment therewith, and the entire engagement and connection of the folding parts is such that the back folds with the legs and between the legs and into alignment therewith within the uprights upon the folding of the seat within the uprights and the seat when folded overlies the back and legs and is laterally offset therefrom.

Certain meritorious features reside in the mounting of the back between the legs and between the uprights to accomplish the described folding thereof and the mounting of the seat between the uprights and the legs and the connection thereof with the legs so that the seat limits the unfolding movement of the legs and the legs limit the unfolding movement of the seat and the folding of the seat serves to fold the legs and back within the uprights.

Another meritorious feature lies in the relative arrangement of the pivotal supports of the folding parts and particularly the specific connection between the seat and the legs whereby the seat is thrown eccentrically with respect to the legs during the folding operation so that while all the parts are folded within the uprights the seat is laterally offset therein with respect to the legs.

Other meritorious and worthwhile features will more fully appear from the following specification, appended claims and accompanying drawing, wherein:

Fig. 1 is a vertical sectional view through a holding chair embodying my invention showing the chair unfolded.

Fig. 2 is a view taken on the same line as Fig. 1 showing the chair folded.

Fig. 3 is a fragmentary sectional view taken on the line 3-3 of Fig. 2.

Fig. 4 is a perspective of an end fragment of the seat showing the pivotal gudgeon, and

Fig. 5 is a view of a fragment of the chair taken on the same line as Fig. 1 showing a slightly modified form of construction.

My folding chair includes a pair of uprights 10 (only one of which is here shown) connected in spaced apart relationship at their upper ends by a back member 12 and a brace rod 14 and at their lower ends by a brace rod 16. A pair of legs 18 (only one of which is here shown) are held in spaced apart relationship at their lower ends by a rod 20 and are pivotally supported at their upper ends between the uprights upon pins 22, one of which is provided for each leg.

A back 24 is pivoted between the legs at its lower end upon pins 26 and is slidably pivotally supported at its upper end by pins 28 which are mounted within slots 30 formed in the uprights so that the pin 28 may travel therethrough in the unfolding and folding of the chair.

There is formed upon the inside of each leg a linearly extending narrow slot 32. A seat 34 is pivoted upon a rod 36 between the uprights intermediate its ends. The rear end of the seat carries a pivotally supported angular gudgeon 38 mounted for pivotal movement upon a pin 40 and provided with a flat thin lip 42 which is received within the slot 32 to travel therethrough.

When the chair is folded from the position shown in Fig. 1 to that shown in Fig. 2, the elevation of the front end of the seat draws the legs within the uprights, the lip 42 traveling through the slot 32 in the legs, until the back 24 and the legs 18 are arranged substantially in alignment within the uprights and the seat 34 is thrown laterally forwardly by virtue of its connection with the legs and also that it is pivoted at 36 forwardly of the pivotal connection of the back and legs with the uprights until the seat when folded overlies the legs and back and is laterally offset the legs and back within the uprights.

When the chair is unfolded the legs are swung rearwardly by the seat and the connection between the legs and seat is such that the rearward movement of the legs is 100

limited by the seat and the upward movement of the rear end of the seat is limited by the legs. During the folding operation it will be seen that the pin 28 will travel downwardly in the slot 30 in the uprights and when the chair is unfolded the pin will travel upwardly therein.

In Fig. 5 a slight modification is shown: namely, the slot 32 is continued upwardly 10 beyond the point shown in the other figures of the drawing and the back 24 is mounted upon a stationary pivot 280 in the uprights and upon a slidable pivot 260 within slots 32 above the lip 42 of the gudgeon 38 so that the lower end of the back has a slidable 15 movement with respect to the legs rather than the upper end of the back as shown in the first four figures of the drawing.

What I claim is:

1. A folding chair having a pair of uprights, a pair of legs pivoted therebetween to be swung outwardly therefrom into supporting relationship therewith or to be folded therebetween, said legs having longitudinal slots formed on their inner sides, a seat pivoted intermediate its ends between the uprights, a gudgeon pivoted to each side of the seat at its rear end having a portion slidably arranged within the slot of the adjacent leg to travel therethrough to limit the upward movement of the rear end of the seat and the rearward movement of the legs, a back pivoted at its upper end between the uprights and having a gudgeon at its lower end upon each side arranged within the slot of the adjacent leg to travel therethrough upon the folding and unfolding of the chair, said seat gudgeon having that portion which is engaged in the slot of the leg offset rearwardly its pivotal connection with the seat whereby upon the folding of the chair the seat is thrown forwardly of the legs and in overlapping relationship with the back within the uprights.

2. A folding chair having a pair of uprights, a pair of legs pivoted to the uprights to be swung outwardly therefrom into supporting relationship with respect thereto or to be folded between the uprights, said legs having linearly extending slots formed upon their inner sides, a seat pivoted between the uprights adjacent the forward edge thereof to fold therein or to be unfolded, gudgeons arranged on opposite edges 55 of the seat having rearwardly offset portions adapted to travel within the slots in the legs to limit the upward movement of the rear end of the seat and the rearward movement of the legs and adapted to draw 60 the legs within the uprights upon the folding of the seat and to spread the legs away from the uprights upon the unfolding of the seat, and to throw the seat forwardly of the legs upon the folding of the legs, a 65 back pivotally supported at its upper end

between the uprights adjacent to the rear edge thereof and provided on opposite sides at its lower end with gudgeons arranged within said slots to travel therethrough to cause the back to fold with the legs within 70 the uprights.

In testimony whereof, I, GEORGE D. SCHERMERHORN, sign this specification.

GEORGE D. SCHERMERHORN.
